FIG. 1

FIG. 2

Bertha E. Feist ^{INVENTOR.}
BY Wm. H. Stock
ATTORNEY

UNITED STATES PATENT OFFICE.

BERTHA E. FEIST, OF NEW YORK, N. Y.

DESIGN FOR A RAG DOLL OR ARTICLE OF SIMILAR NATURE.

59,467.

Specification for Design.

Patented Oct. 25, 1921.

Application filed June 23, 1921. Serial No. 479,926. Term of patent 7 years.

To all whom it may concern:

Be it known that I, BERTHA E. FEIST, a citizen of the United States of America, residing at New York city, county and State of New York, have invented a new, original, and ornamental Design for a Rag Doll or Articles of Similar Nature, of which the following is a specification, reference being had to the accompanying drawing, forming part hereof, in which—

Figure 1 is a face view of one side of a rag-doll having my new design, and Fig. 2 is a similar view of the other side thereof.

I claim:—

The ornamental design for a rag doll or article of similar nature as shown.

Signed at New York city, N. Y., this 18th day of June, 1921.

BERTHA E. FEIST.
